UNITED STATES PATENT OFFICE

LESTER L. LEWIS, OF NEW CASTLE, PENNSYLVANIA, ASSIGNOR OF TWO-THIRDS TO
BLAIR STRIP STEEL COMPANY, OF NEW CASTLE, PENNSYLVANIA, A CORPORATION
OF PENNSYLVANIA

ART OF ANNEALING METAL WORK

Application filed February 17, 1930. Serial No. 429,135.

This invention relates to improvements in the art of heat treating and cooling metal work for increasing ductility without discoloration, and more particularly to the art 5 as set forth in my two co-pending applications, one filed December 2, 1929, designated by Serial No. 411,179, now Patent No. 1,777,978, dated October 7, 1930, and the other filed February 4, 1930, designated by 10 Serial No. 425,812, now Patent No. 1,835,411, dated December 8, 1931.

The essential object in view is characteristically similar to that of the art as set forth in said co-pending applications, and 15 that object is attained by a modified mode of treatment as will hereinafter become apparent.

Among the more detailed objects in view is the securing of a high degree of ductility 20 of the metal work annealed at a minimum cost, and the maintenance of the superficial condition of the work substantially or wholly free from discoloration.

With these and other objects in view as 25 will hereinafter in part become apparent and in part be stated, the invention comprises the heat treating or metal work free from any especial attempt at sealing, and the subsequent cooling of the work under conditions 30 precluding surface discoloration.

The invention comprises certain other novel steps and combinations of steps in the art of heat treating metal work as will be hereinafter specified and subsequently particularly pointed out in the appended claims.

The invention is adapted to be practiced by the use of any of many well known forms 40 of heat treating apparatus, and almost any good set of such apparatus can readily be used; but, for purposes of preferred exemplification, any of the structures disclosed in my above-identified co-pending applications may be effectively used, and to the end of clearly and more readily disclosing the invention one of the forms of my second-

above-identified application is illustrated in the accompanying drawing for purposes of concrete reference in the description of the application of the invention, and in which drawing,—

Figure 1 is a top plan view of a fragment 50 of a furnace and work-receiving, movable housing well adapted for the carrying out of the present invention.

Figure 2 is a transverse section taken on 55 the plane indicated by line 2—2 of Figure 1.

Figure 3 is a similar view of the same after removal from the furnace and after preparation for the cooling of the metal.

Referring to the drawing by numerals, 1 60 indicates an annealing furnace which may be of any well known or approved type and which is preferably provided with the usual antifriction tracks 2, 2, sustaining and directing the work-carrying housing into and 65 out of the furnace. The work-carrying housing may be formed or made up in any preferred or well known manner, one type of housing in use in standard practice consisting of a tray 3 having grooves 4 in its under 70 face to receive the balls or antifriction devices 2. A casing 5, commonly referred to as an annealing pot, is mounted on the tray 3, the pot being of sufficiently reduced dimensions with respect to the upstanding flange 75 6 of the tray as to leave a groove-like, open space 7 between the side wall of the pot and the upstanding flange of the tray. The work indicated at 8 is mounted on the tray 3, and the pot 5 is lowered over the work in the 80 preparation for the annealing operation. A channel or port 9 is arranged in the flange 6 having a discharge opening 10 directed into the space 7, and a connection, nipple, or the like, 11, communicates with the port 9 and during a portion of the operation is connected with a gas supply pipe 12. A similar port 13 is arranged about the wall of the pot 5 and provided with a discharge opening 14 and an intake or supply nipple 15, which 85

90

latter is during a part of the operation connected with a gas supply pipe 16. It should be understood that the nipples 11 and 15 are adapted to be detachably connected with the 5 pipes 12 and 16 respectively for convenience in the carrying out of the operation as hereinafter set forth. It should also be understood that any of numerous other arrangements may be made for the supplying of gas 10 to the area 7, such, for instance, as are indicated in my two above-identified, co-pending 15 applications.

While it should be clearly understood that the above specified equipment is well adapted 20 for the carrying out of the present invention, the invention is in no sense limited to such equipment, but may be more readily disclosed by specific reference to the preferred manipulation with respect to such 25 equipment. With this understanding in the carrying out of the present invention, work 8 is supplied to the housing made up of tray 3 and pot 5. This work must, however, to give the best results, be entirely or substantially 30 free from carbonaceous matter on its surface, such as the presence of certain rolling lubricants containing carbon. Either the work must be rolled dry or rolled with the use of a lubricant wholly free from carbon, or, if a carbonaceous lubricant be employed 35 during rolling, the work must be thoroughly cleansed and freed from any deposits of such lubricant before being assembled in the housing as just stated. While it is true that when 40 heat treating iron or steel which has been rolled with rolling oil containing carbon good results may be obtained, the presence of any appreciable amount of such oil is liable to produce a spot or area of discoloration, whereas with the total absence of any 45 such lubricant the finished product is bright and reflector-like in appearance similar to polished nickel.

The work being thus assembled in the 50 housing and the pot 5 being arranged on the tray 3 to enclose the work, no provision is or need be made to seal the work prior to introduction into the furnace 1. It has previously been standard practice to provide a 55 comminuted seal in the area 7, and sometimes also directly beneath the lower edge of the pot 5 before the work is introduced into the annealing furnace, but, according to the present invention, such provision or pre- 60 caution is not at all necessary. Of course, the pot 5 and tray 3 should be free from flaws or cracks which are liable to leak during cooling, as any appreciable leakage in this way would largely detract from the desirable 65 results to be obtained, and would be liable to produce discoloration on the surfaces of the work.

When the parts are thus assembled, as indicated in Figure 2, the housing made up 70 of pot 5 and tray 3 is moved along the track

2 into the furnace 1 where the temperature of the work is raised to the requisite degree and maintained for the required time for effective annealing. Then the work in its casing, as stated, is withdrawn from the furnace. At the time of introduction into the furnace, the pipes 12 and 16 will not have been connected to their respective nipples 11 and 15, but just as soon as the work has been withdrawn from the furnace, the operator 75 deposits a comminuted filler or seal into the area 7, filling the same at least to the level of the discharge openings 10 and 14, and preferably entirely filling the said area up to the level of the upper edge of the flange 6 of tray 3 all about the pot 5. It is also preferable to tamp the comminuted material somewhat to insure a reasonable degree of compactness thereof. When the filler or seal 80 seen at 17 in Figure 3 has been thus applied, gas under pressure is supplied to the ports 9 and 13 and caused to discharge through the openings 10 and 14 under sufficient pressure to effectively resist the tendency of the atmosphere to penetrate the comminuted seal 17 in response to the forming vacuum in the pot 5 with the cooling of the contents of the pot. The comminuted material 85 17 may be iron filings or iron chips, or sand, and when sand is employed, a fine grade free from loam is preferred, such as commonly referred to as lake sand. The supply pipes 12 and 16 may be connected to their respective nipples 11 and 15 at any time convenient to the operator relative to the filling 90 of the seal 17 in the area 7, it being understood that the said connections are made and the filling in of the sealing matter completed as promptly as practicable after the withdrawal of the parts from the source of heat. The connections must be completed and the 95 gas turned on by the time cooling has progressed to that point where a partial vacuum begins to form within the pot 5. This does not occur for some little time, perhaps as 100 much as twenty minutes after the withdrawal of the average pot 5 from the furnace, but it is well to have the seal applied and the gas turned on without any undue delay immediately on withdrawal of the work from the furnace. The pressure of the gas supplied must be sufficiently great to resist atmospheric pressure, and the pipes 12 and 16 with their nipples 11 and 15 must be proportioned with respect to the discharge openings 10 and 14 to insure a substantially uniform distribution of gas entirely about the pot and tray. While I have illustrated two sources of gas supply to the area 7, one in the form of the port 9 and its discharge 10 and the other in the form of the port 13 and its discharge 14, one or the other of these sources of supply may be successfully omitted, but I prefer the balanced action 115 incident to the use of both.

It is well understood by all workers in the present art that iron or steel at high temperature oxidizes readily, and, therefore, the cooling operation must progress to the 5 point where the work is below that temperature at which surface discoloration will occur incident to contact with the air before the gas supply is turned off from ports 9 and 13 or the housing is opened.

10 Generic claims for the broader aspects of the process invention of this application are presented in my co-pending application Serial No. 479,051, filed August 30, 1930, as a division of my above-identified application, now Patent No. 1,777,978.

What is claimed is:

1. In the art of annealing metal work, heat treating metal work in an unsealed container of the type admitting passage of atmosphere 20 to and from the interior when unsealed, cooling the work within the container in air, sealing the work in the container at the beginning of the cooling step, and maintaining the container completely sealed against discoloration agents until the cooling operation is finished.

2. In the art of annealing metal work, heat treating metal work in an unsealed condition and sealing the metal work subsequent to the 30 heat treatment, and cooling the sealed work in air, and treating the seal during cooling for preventing access of discoloration agents through the seal.

3. In the art of annealing metal work, the 35 steps of applying a comminuted seal to the housing for the work subsequent to heat treatment of the work, cooling the work within the housing in air, and distributing gas to the comminuted seal during cooling of the metal work for preventing access of air to the work.

4. In the art of annealing metal work, the steps recited in claim 3 in which the gas is supplied under pressure sufficient to counter- 45 balance atmospheric pressure and exclude atmosphere.

5. In the art of annealing metal work, heat treating metal work to a sufficiently high degree and for the requisite time for annealing 50 purposes while the work is in an unsealed condition, discontinuing the heat treatment, and thereafter applying a seal of comminuted material and delivering gas to said seal under pressure sufficient for excluding from the work discoloration-producing influences.

6. In the art of annealing metal work, preparing metal work for annealing free from surface carbon, raising the work to annealing temperature for the requisite time, and subsequently 60 cooling the work within a housing in air, and sealing the housing against ingress of discoloration agents for preserving the work against discoloring action during the cooling operation.

65 7. In the art of annealing metal work, pre-

paring metal work for annealing free from surface carbon, raising the work to annealing temperature for the requisite time, subsequently cooling the work within a housing in air, and sealing the housing against ingress 70 of discoloration agents for preserving the work against discoloring action during the cooling operation, and continuing the seal until the work has cooled below that temperature at which atmospheric contact with the 75 work is liable to produce discoloration.

In testimony whereof I affix my signature.
LESTER L. LEWIS.
